UNITED STATES PATENT OFFICE.

EDOUARD FAUCONNIER, OF NEVERS, AND ALBERT SIMPÈRE, OF PARIS, FRANCE.

CARBURETOR.

Application filed December 20, 1923, Serial No. 681,730, and in France September 3, 1923.

When producing combustible gases for use as fuels for lighting, heating and similar purposes such for instance as the singeing of fabrics, it is most desirable to obtain in all places and during any season, irrespective of the hygrometric state of the air, a combustible gas resulting from the homogeneous intermingling of air and vaporized gasoline or the like and having as uniform a composition as is required so as to afford a substantially uniform calorific power. Now, it is a well known fact that the atmospheric air drawn into the appliances intended for producing carbureted air frequently contains, particularly at certain periods of the year and in certain regions of the earth, an important amount of moisture. When coming in contact with the gasoline in the course of evaporation, the said moisture condenses either as mist or as frost and by thus settling down as misty or frosty film upon the surface of the gasoline more or less prevents the latter from properly contacting with the incoming air, as a result of which the richness of the carbureted air changes. Furthermore, when the feed of carbureted air is interrupted, the evaporation of the gasoline or other fuel continues, this results in the production of too rich a gas mixture, this being also partly due to a slight reheating of the air.

The primary object of the present invention is to obviate the drawbacks hereinbefore referred to by providing the hitherto commonly constructed appliances for producing carbureted air of the various types with a carbureting casing having a device based on the refrigeration principle for condensing the moisture of the atmospheric air, the air thus deprived of its moisture being thereafter intermingled with the evaporated gasoline deprived to a carbureted air of substantially uniform composition.

A further object of the invention is the provision of a casing for carbureting the air whilst at the same time condensing the moisture therein contained, the refrigerating walls of which are constituted by the walls of the channels through which circulates the gasoline intended for carbureting the said air having previously been deprived of its moisture, as above described, whereby without the addition of any moisture to the air it becomes possible to continuously and cheaply deprive of its moisture whilst warm-

ing up the carburetor and consequently to enhance its output and to permit the use of heavier hydrocarbons.

With these and other objects in view as will incidentally appear hereinafter, the invention comprises the novel arrangement, construction and combination of parts that will now be described in detail with reference to the accompanying drawing and will be more particularly emphasized in the appended claims.

In the drawing:—

Figure 1 is a vertical sectional view on the line $z-z$, Fig. 2, of the casing for refrigerating and carbureting the air, which casing is embodied in the appliance herein-after described.

Figure 2 is partly a vertical sectional view on the line $x-x$, Fig. 1, and partly an elevational view of the said casing.

Figure 3 is partly an elevational view and partly a sectional view of an appliance according to the invention comprising a drum unit for drawing in the fresh air and for expelling out the carbureted air, a casing for condensing and carbureting the fresh air and a device for distributing the liquid fuel.

Figure 4 is a perspective view of a portion of the corrugated gauze on which the liquid fuel flows during the carbureting of the air which has previously been deprived of its moisture.

In all these figures similar parts are designated by corresponding reference numerals.

According to the invention within a water vat 1 of rectangular cross-sectional shape carried horizontally by brackets 2 and supported by four vertical pillars 3 held in spaced relationship by a top frame 4 is rotatably arranged a hollow drum unit 5 provided with a plurality of partitions 6 and pierced with longitudinal slots 7 adjacent said partitions. The carbureted air drawn in by the rotation of this drum unit is expelled into a laterally disposed receptacle 8 mounted concentrically to its axis and communicating through a goose-neck shaped pipe 9 with a suitable gasometer (not shown). The vat 1 is closed at its upper end by an outwardly bowed lid 10 the edge of which dips into a hydraulic seal 10^a. Said vat 1, drum unit 5 and lid 10 may be for the sake of clearness termed an aspirator, the function of which appears herein-after. Between the said lid 10 and the cir-

cumferential wall of the rotatable drum unit 5 is arranged the casing unit B adapted for condensing the moisture contained in the incoming air and for carbureting the 5 said air thus deprived of moisture.

The condensing or carbureting device or casing unit for the air is supported by two or more arch-shaped members 11 formed of tubes welded at their ends to the side edges 10 of tapered troughs 12 carried horizontally by squares 13 depending from rings 14 secured to the pillars 3; other tubes 15 are arranged transversely to the arch-shaped members 11. On the said tubes 11 and 15 15 is advantageously spread a large-meshed gauze 16 extending from the lower mouth of the carbureting channels E formed by the two sloping portions of the casing B (see Figure 1) to a position overhanging the 20 troughs 12.

The lid 10, casing B, arch-shaped members 11 and troughs 12 are bodily connected and carried en bloc on the squares 13, the vat 1 being hermetically closed owing to the 25 dipping of the lid edge into the hydraulic guard 10^a.

On the top frame 4 are carried the usual devices required in the type of appliance herein described, to wit; a gasometer, a wind- 30 lass and an electric motor for rotating the drum unit. Neither of these devices forming the subject matter of the invention is shown and described. The fuel tank 18 is similarly carried on the said frame 4. All 35 these devices are fixedly secured to this frame which therefore must be perfectly horizontal. In order to ensure the hori- zontality of the frame, top and bottom nuts 17 are provided on the top and lower ends 40 of the pillars. By suitably screwing up or unscrewing the said nuts, it becomes possible to take up any slant that might take place in the position of the vat 1 or frame 4.

The fuel tank 18 is supported above the 45 frame 4 by means of legs 19 and is provided with an overhead chamber 20 and opposite said chamber with a trough 21 positioned underneath the level of the bottom of the said tank. By this arrangement, it is pos- 50 sible for a scoop 22 provided at the ex- tremity of an elongated pipe 23 pivotally mounted upon a pin 24 to intermittently dip the liquid fuel e' out of the trough 21 and to pour it through the opposite nozzle- 55 shaped extremity 25 of the said pipe 23 into a funnel 26 communicating through a suit- able trap 27 with the condensing and carbureting casing unit B. On the removable cover 28 of the said chamber 20 are secured 60 an air tube 29 and an indicator 30 of the level of the liquid fuel.

The condensing and carbureting casing unit B represented separately in Figures 1 and 2 is of the general shape of a prism 65 closed at its two ends 31 and having an up-

per flat face 32, two equally slanting side faces 33 and two other equally slanting faces 34 placed opposite to the said upper flat face 32 and between the said slanting faces 33, 34, flat faces 35 apertured in the greater part 70 of their length. Centrally of the top flat face 32 is welded a cylindrical pipe 36 whose outer part is screw-threaded to receive an intake tube 37 (Fig. 3) through which the atmospheric air enters into the casing B. 75 On the lower part of the said pipe 36 is welded a horizontal diaphragm 38 extending over the greater portion of the length of the casing B. Above the said diaphragm 38 the pipe 36 is formed with side apertures 80 39. Finally the bottom part of the pipe forms a seat for a valve 40 provided with a shank 40^a by means of which it is possible to adjust said valve with respect to its seat.

Within the outer casing B is arranged an 85 inner casing only extending over a part of its length. This inner casing whose walls are symmetrical relatively to the vertical axis o—o is limited at its lower end by the equally slanting walls 41 and at its upper end by the equally slanting walls 42, the latter walls being continued at their upper end by the vertical longitudinal walls 43 which in turn are continued at their top end by the horizontal diaphragm 38. The vertical side 90 walls 44 (see Fig. 2) of the said inner cas- ing are disposed parallel to the end walls 31 of the outer casing B. Extending from the bottom 41, in parallelism to the axis o—o and between the walls 44 to a short distance 95 above the diaphragm 38, are a pair of vertical partitions 45. These partitions 45 are connected at their top ends by an inverted V shaped roof 46; below the edge of this roof 46 each of the said partitions 45 is 100 pierced with a row of holes 47. The slanting channels E limited by parallel walls 41 and 42 are opened on the side faces 35 of the outer casing B.

The arrangement of the inner casing 110 within the outer casing B provides on both sides a vertical passage C which establishes a lateral communication between the upper compartment D and the lower compartment D'. As indicated by the full line arrows in Figures 1 and 2, the atmospheric air which is drawn in owing to the rotation of the drum unit 5 enters through the apertures 39, passes through the compartments D and escaping through the lateral passages C reaches the compartments D' whereafter it 115 ascends through the central chimney F and passes through the holes 47 to become saturated with liquid fuel and flow out of the casing B through the opened slanting chan- nels E. The air thus carbureted gradually 120 fills up the compartments of the rotatable drum 5.

The carburetor is constructed by welding 130 against the inner slanting walls 41 and 42

of the two channels E suitable lengths of corrugated gauze as shown in Figure 4 so that thus the flat portion 57 if the said gauze is welded to the said walls 41 and 42 and 5 the corrugations 56 protrude beyond the said walls edgewise of the channels E. The said corrugations 56 are arranged at right angles to the plane of the mouth of the said channels. Another length of gauze 48 is held 10 taut between the lid 46 and the upper end of each channel E throughout the length of the inner casing.

On the external face of the lid 46 is applied the pipe 27 adapted for feeding the 15 liquid fuel into the carburetor. This pipe is perforated as at 52 (Fig. 2) all along the tangent contacting with the said lid 46 so as to permit the fuel that percolates through the said perforations to be distributed on 20 the gauze 48 and thence through the meshes of the other gauze 57. The drops of fuel that have not been evaporated and carried away by the air passing through the channels E fall on the said gauze portion 57, 25 welded to the lower wall 41 as above described, whereas the fuel drops that escape at the end of the said channels E continue to travel upon the large-meshed gauze 16 supported by the arch-shaped members 11 30 and are thus maintained in contact with the more or less carbureted air travelling towards the drum 5. In the event of fuel drops reaching the lower end of the gauze 16, they are bound to fall into the troughs 25 12. The fuel generally follows the path as indicated by the arrows (see Figs. 1 and 2) and by the arrows e (see Fig. 3). The carbureted air travels in the direction indicated by the arrows a g (see Fig. 3) and 40 the resulting gas flows away along the path as indicated by the arrows g.

It will be understood that the outer air, by contacting the walls 41 and 42 of the two channels E (cooled by the evaporation 45 of the fuel) is caused to condense its entrained moisture against the said walls. This condensed moisture collects in the bottom portion 34 of the casing B, escapes through the holes 58 and drips into the 50 water vat 1. The air thus having been deprived of its moisture ascends through the chimney F and is afterwards fit for becoming properly saturated with fuel by contacting with the gauzes 48 and 57.

55 From the foregoing it will be apparent that a carbureting apparatus is provided which may advantageously be used whenever, it may be necessary because of the high moisture content of the atmospheric air to deprive the air to be carbureted of its moisture before submitting same to the carburation proper, the condensing and carbureting operations being, as above stated, performed most simply and efficiently in the same apparatus.

It must be understood that the form of this invention herewith shown and described is to be taken as a preferred embodiment of the same and that various changes in the shape, size, number and more generally in 70 the arrangement of the several parts may be resorted to without departing from the spirit of the invention or the scope of the subjoined claims.

What we claim and desire to secure by 75 Letters Patent is:—

1. A carburetor of the character described, comprising a carbureting chamber having an air inlet and a carbureted air outlet, and a casing for dehydrating the 80 air supplied to the chamber, said casing enclosing all of said chamber except the outlet.

2. A carburetor of the character described, comprising a casing having an air inlet, a chamber within said casing having opposite 85 open ends extending through opposite walls of said casing, and means for supplying fuel to the inside walls of said chamber, said chamber having openings whereby the air in said casing may pass around said chamber, 90 into said chamber through said openings, and out of said chamber through said open ends.

3. A carburetor of the character described, comprising a chamber with open ends and 95 openings in its under side, means for supplying fuel to the inside walls of said chamber, and a casing enclosing all of said chamber except the open ends, and having an inlet for air whereby such air may pass around 100 said chamber, into said chamber through said openings, over said fuel to become carbureted thereby, and out of said open ends.

4. A carburetor of the character described, as claimed in claim 3, including means in 105 said chamber for directing the fuel in a spread condition along the inside walls thereof, whereby the walls become sufficiently cool to condense moisture in the air passing over the outside of the chamber, and 110 whereby the spread fuel becomes preheated by such condensation.

5. A carburetor of the character described, as claimed in claim 3, including means in 115 said chamber for directing the fuel in a spread condition along the inside walls thereof, said means comprising corrugated gauze carried by the walls of the chamber.

6. A carburetor of the character described, as claimed in claim 3, including means in 120 said chamber for directing the fuel in a spread condition along the inside walls thereof, said means comprising corrugated gauze carried by the walls of the chamber, and a perforated fuel supply pipe positioned to 125 supply separate streams of fuel to spaced portions of the gauze.

7. A carburetor of the character described, as claimed in claim 3, in which said chamber has a central inverted U-shaped portion and 130

slanting lateral portions, said means comprising corrugated gauze carried by the walls of the slanting portions, gauze strips spanning the vertical parts of the U-shaped portion, and a perforated supply pipe in the horizontal part of the U-shaped portion, whereby fuel flows from the pipe across and through said gauze strips to the upper and lower walls of the slanting portions respectively and thence in a spread condition toward the open ends of the chamber.

8. A carburetor of the character described, as claimed in claim 3, in which said chamber has a central inverted U-shaped portion, and in which said openings in the under side are in the lateral walls of the space embraced by said U-shaped portion.

9. In a carburetor of the character described, the combination with a chamber having an air inlet and a carbureted air outlet, and means for supplying fuel to the inside walls of said chamber, of corrugated

gauze carried by said walls for spreading the fuel, said gauze comprising a single strip having spaced depending portions constituted by folded portions of said gauze.

10. A carburetor of the character described comprising a carbureting chamber, means for supplying fuel to said chamber, a casing partially enclosing said chamber and having a top air inlet, said chamber and casing having coincident outlet openings, an aspirator enclosing all of said casing except the air inlet, an arched support in said aspirator for said casing, gauze carried by said support and troughs at opposite ends of said support whereby excess unvaporized fuel escaping from said outlet openings will be guided by said gauze to said troughs.

In testimony whereof we have signed our names to this specification.

EDOUARD FAUCONNIER.
ALBERT SIMPÉRE.
